TAPPING DEVICE

Chester E. Sprague, Portland, Oreg.

Application September 29, 1947, Serial No. 776,661

1 Claim. (Cl. 10—89)

1

This invention relates generally to the tapping of holes with power-driven tools and particularly to a tapping device.

The main object of this invention is to provide a means for frictionally holding a tap in a thread-cutting direction and positively holding it in a withdrawing direction.

The second object is to reduce the breakage of taps and to avoid the necessity of close observance of the operation to insure the completion of the threading operation without danger of an abnormal load breaking the tap.

I accomplish these and other objects in the manner set forth in the following specification as illustrated in the accompanying drawing, in which:

Fig. 1 is a longitudinal section through the device.

Fig. 2 is a transverse section taken along the line 2—2 in Fig. 1.

Fig. 3 is a transverse section taken along the line 3—3 in Fig. 1.

Fig. 4 is a section taken along the line 4—4 in Fig. 2.

Fig. 5 is a perspective view of the wedge element.

Similar numbers of reference refer to the same or similar parts throughout the several views.

Referring in detail to the drawing, there is shown a piece of work 10 which is held in the work holder of a tapping machine such as is now in common use in which the work is turned in either direction under power and control of the machine (not shown) while the tap 11 is relatively still except that it is advanced to be held frictionally while thread cutting, but to be held positively when backing out of the thread. It is this feature which forms the basis of the present invention.

There is shown a support 12 for a tapping spindle 13 which is held against rotation by means of a key 14.

On the spindle 13 is formed a cylindrical housing 15 within which is threaded a bearing 16 for the cylindrical portion 17 of the tap holding chuck 18 in whose head 19 is held a tap supporting collet 20 by means of a set screw 21. The shank 22 is provided with a square end 23 which is held between the four screws 24 extending into the chuck 18 and held by the lock nuts 25. On the portion 17 is formed an enlarged end 26 having a V groove 27 formed therein which is occupied by the friction dog 28 which is secured to the housing 15 by means

2

of the screws 29. The cross section of the dog 28 is the same as that of the groove 27. The dog 28 is longitudinally curved as shown.

Tangential to the groove 27 is the locking dog 30 which is slidable in the auxiliary housing 31 formed on the housing 15.

The dog 30 is provided with a reduced shank 32 which receives the compression spring 33 mounted on the pin 34 within the adjusting cap 35 which is screwed onto the threaded end 36 of the housing 31.

It will be noted that the dog 30 is flattened to form a V-shaped wedge whose small end 37 fits the groove 27, that is, the faces 38 will wedge 15 into the groove 27 under the urging of the spring 33.

The operation of the device is as follows:

Assuming that a thread is to be cut in the hole 39 of the work 10 and that the work is 20 being revolved by suitable power and moved toward the stationary tap 11. As the tap begins to cut its thread it is held against rotation by the friction between the dog 28 and the groove 27 as set up by the end thrust from the 25 tap 11. If the tap should bottom before the rotation of the work 10 is reversed (either manually or automatically as the case may be) or an abnormal resistance be offered to the cutting operation, then the tap 11 will yield to the rotation 30 of the work 10, thereby protecting the tap against breakage.

When the rotation of the work 10 is reversed, the dog 30 is wedged into the groove 27 due to the friction plus the action of the spring 33, 35 producing a positive holding action for the tap 11 while it is being withdrawn.

It will be understood that the collet 20 may be replaced by a button die or solid type die without departing from the spirit of this invention.

I am, of course, aware that numerous forms of tapping devices have been constructed in the past. I, therefore, do not claim such devices broadly but I do intend to cover such forms 45 and modifications thereof as fall fairly within the appended claim.

I claim:

A tapping device having in combination a 50 housing adapted to be held in the turret of a tapping machine, said housing having a cylindrical interior, a tap holding chuck journalling in said housing, said chuck having a V-groove formed around same, said chuck having a limited endwise motion with relation to said housing, an 55 arcuate shoe in said groove secured to said

housing, a wedge slidably mounted in said housing tangentially with relation to said groove, a spring for urging said wedge into engagement with the sides of said groove, the holding action between said housing and chuck in a tapping direction being due to the friction between said shoe and one side of the groove, and the holding action between said housing and chuck in a tap withdrawing direction consisting of the friction on one side of the arcuate shoe plus 10 the total friction between said wedge and both sides of said groove.

CHESTER E. SPRAGUE.
